(57) **CLAIM**

I claim the ornamental design for a floor dowel sleeve, as shown and described.

DESCRIPTION

FIG. 1 is a rear perspective view of a floor dowel sleeve showing my new design;

FIG. 2 is a rear elevation view of the floor dowel sleeve shown in FIG. 1;

FIG. 3 is a front elevation view of the floor dowel sleeve shown in FIG. 1;

FIG. 4 is a right side elevation view of the floor dowel sleeve shown in FIG. 1;

FIG. 5 is a left side elevation view of the floor dowel sleeve shown in FIG. 1;

FIG. 6 is a top plan view of the floor dowel sleeve shown in FIG. 1;

FIG. 7 is a bottom plan view of the floor dowel sleeve shown in FIG. 1;

FIG. 8 is a disassembled perspective view of top and bottom pieces of the floor dowel sleeve shown in FIG. 1;

FIG. 9 is a rear elevation view of the bottom piece shown in FIG. 8;

FIG. 10 is a rear elevation view of the top piece shown in FIG. 8;

FIG. 11 is a front elevation view of the bottom piece shown in FIG. 8;

FIG. 12 is a front elevation view of the top piece shown in FIG. 8;

FIG. 13 is a right side elevation view of the top and bottom pieces of the disassembled floor dowel sleeve shown in FIG. 8;

FIG. 14 is a left side elevation view of the top and bottom pieces of the disassembled floor dowel sleeve shown in FIG. 8;

FIG. 15 is a top plan view of the top and bottom pieces of the disassembled floor dowel sleeve shown in FIG. 8;

FIG. 16 is a bottom plan view of the top and bottom pieces of the disassembled floor dowel sleeve shown in FIG. 8; and,

(Continued)

FIG. 17 is a perspective view of the floor dowel sleeve shown in FIG. 1 illustrated in engagement with an unclaimed dowel and supported by an unclaimed dowel basket assembly.

In the drawings, the broken lines depict unclaimed portions of the floor dowel sleeve in FIGS. 1, 3, 6, 8, 9, and 11-16 and illustrate environmental subject matter in FIG. 17. The broken lines form no part of the claimed design.

1 Claim, 17 Drawing Sheets
